PUNCHBOARD GAME DEVICE

Vernon K. Smith, Boise, Idaho

Application March 27, 1950, Serial No. 152,018

1 Claim. (Cl. 273—139)

1

This invention relates to a punchboard game device, and more particularly to a punchboard formed in a manner to resemble a slot machine and operative with an electric circuit which is excited upon the removal of a selected punch from a punchboard.

It is an object of this invention to provide a punchboard supported in a cabinet, the cabinet being designed and formed to resemble a slot machine, the punchboard device of this invention having an electrical attraction circuit which is activated upon removing a punch from the punchboard. A series of lights, chimes, and other attraction devices are connected to the electrical circuit which is excited upon the removal of a punch from the punchboard.

Another object of this invention is to provide a game device of this kind having a counter connected to the electrical attraction circuit for registering the number of punches which have been removed from the punchboard.

An alarm is also connected to the electric circuit for warning an attendant when an operator is using the machine in an unauthorized manner.

A further object of this invention is to provide a guide member or supporting device in the cabinet which is to be matched by the particular design of the punchboard in such a manner that only punchboards designed particularly for the machine may be inserted therein. The punchboards are removably supported in the cabinet so that they may be replaced when any one of the punchboards has been depleted. An electrical switch is connected in the attraction circuit and is operated by the insertion of a proper type of punchboard.

A still further object of this invention is to provide a punchboard which is provided with bores for supporting the punches therein, the bores being formed at various angles to the front surface of the punchboard in a manner to provide for the prevention of removal of a plurality of punches at a single time in an unauthorized manner.

Yet another object of this invention is to provide an electric motor which is operatively connected to the attraction circuit and is operative for rotating an electric contact member which is connected to a separate electric alarm or attraction device which is operative only when the rotatable contact member comes to rest in contact with a fixed contact member, such motor and contact members constituting a chance element which is to be rewarded by a free play when such contacts remain in engagement after a player has completed a play on the machine.

2

With the above and other objects in view, my invention consists in the arrangement, combination and details of construction disclosed in the drawings and specification, and then more particularly pointed out in the appended claim.

In the drawings:

Figure 1 is a perspective view of the front and one side of the game device constructed according to an embodiment of my invention;

10 Figure 2 is a longitudinal section taken behind the front face of the cabinet and looking rearwardly therein;

Figure 3 is a transverse section taken on the line 3—3 of Figure 2;

15 Figure 4 is an electrical wiring diagram of the electric circuit embodied in the game device;

Figure 5 is a front elevation of the rotatable contact members embodied in the chance element of this device and showing the forward face of the motor employed for actuating the rotatable contact member;

20 Figure 6 is a fragmentary side elevation, partly broken away and partly in section, taken on the line 6—6 of Figure 5;

25 Figure 7 is a front elevational view of a support plate carrying electrical switches which are alternatively closed when punches are punched from the associated punch board;

Figure 8 is a rear elevation, partly broken away, of the punchboard supporting means;

30 Figure 9 is a top plan view, partly broken away, of a punchboard particularly designed for use in the game device of this invention;

Figure 10 is a fragmentary transverse section, partly broken away, and partly in section, taken on the line 10—10 of Figure 9.

35 Figure 11 is a rear perspective and fragmentary transverse section, partly broken away, taken on line 10—10 of Figure 9, of a punchboard particularly designed for use in the game device of this invention, showing the slick rear surface thereof, and the manner of retaining the punches spaced inwardly in the board to prevent the snag pieces of retaining paper from extending rearwardly to the rear surface of the board.

40 Referring to the drawings, the numeral 20 designates generally a game device constructed according to an embodiment of this invention. The game device 20 is actually a punchboard supported in a cabinet to resemble a slot machine. It is noted that slot machines have a particular attraction, whereas punchboards have a lesser attraction, and it is an object of this invention to provide a supporting cabinet and a plurality of electrically operated attraction devices to be actuated upon removing a punch from

the punchboard in a manner to resemble a slot machine and in related attractive movement.

The game device 20 is provided with an outer cabinet 21 formed with an enlarged, rectangular base and having a vertically extending front wall 22 terminating at its upper end in a rearwardly and upwardly inclined upper wall 24. A forwardly and upwardly inclined rear wall 25 is terminated at its lower end on the rear edge of the bottom wall 26, and at its upper end on the rear end of the top wall 24, clearly noted in Figure 3 of the drawings. The total assembly of the walls described above is to resemble the general characteristics of a slot machine of the type having the rotatable reels or members which are actuated upon swinging of a lever pivotally mounted on one side thereof.

The front wall 22 is provided with an enlarged, substantially rectangular opening 27, behind which the punchboard 28 is adapted to be supported for removing the punches therefrom by a player of the machine. A channel guide member 29 is fixedly supported on the rear side of the front wall 22 at the lower edge thereof, behind the opening 27, and an upper longitudinally extending channel guide member 30 is fixedly supported on the upper edge of the opening 27 on the rear side of the front wall 22, in the manner clearly noted in Figure 3 of the drawings. The upper channel guide member 30 is positioned at an inclination to the level bottom wall 26 and the lower channel guide member 29, and the punchboard 28 is provided with a peripheral surface whereby the punchboard may be slidably engaged between the channel guide members 29 and 30 for proper positioning therein, so that the punches in the punchboard may be readily reached by a player from the front of the machine reaching through the opening 27.

An intermediate supporting wall 31 is fixed within the cabinet 21, extending upwardly from the bottom wall 26 intermediate the length thereof. A supporting plate 32 is fixedly mounted on the intermediate wall 31 in spaced relation thereto. A plurality of bolts 34 are engaged through the intermediate wall 31 and the supporting plate 32 and a spacer sleeve 35 is engaged about the bolts 34 between the intermediate wall 31 and the supporting plate 32, in the manner clearly noted in Figure 3 of the drawings. The intermediate wall 31 is provided for supporting the supporting plate 32 behind the punchboard 28 within the cabinet 21 and facing the opening 27 on the inner side of the punchboard contained within the guide channels 29 and 30. A plurality of switch elements are adapted to be fixedly mounted on the supporting plate 32 to be actuated by a contact plate 36 suspended behind the punchboard 28 for swinging movement upon removal of a punch therefrom. A pair of resilient coil springs 37 are engaged between the bottom wall 26 and the lower edge of the contact plate 36 and a second pair of resilient coil springs 38 are engaged between the intermediate upper wall 39 and the upper edge of the contact plate 36 for suspending the contact plate for free swinging movement within the cabinet 21.

A plurality of switches 40 are supported on the supporting plate 32 to be actuated upon movement of the contact plate 36 rearwardly in the cabinet 21. The switches 40 include a rear, resiliently mounted contact member 41 and a forward, movable contact element 42, the forward contact element 42 being engageable on the rear surface of the contact plate 36, whereupon the

contact elements 41 and 42 will be moved into engagement upon rearward swinging movement of the contact plate 36, and both elements will move rearwardly to permit the punch to be received between the contact plate 36 and punchboard 28. The switches 40 are arranged with relation to the contact plate 36, whereupon a pair of such contact elements 41 and 42 will be substantially positioned at the corners of the contact plate, as clearly noted in Figure 7 of the drawings. Pegs 43 are carried by the contact plate 36 about the periphery thereof for engagement with the rear side of the front wall 22, to space the contact plate rearwardly therefrom. A center coil spring 44 is engaged between the center of the supporting plate 32 and the center of the contact plate 36 for constantly biasing the contact plate 36 outwardly in the direction of the punchboard 28, and the resiliency of the spring 44 will provide for positioning the contact plate 36 in slightly spaced relation from the punchboard 28, whereby a channel 45 is defined therebetween. A cup-shaped funnel 46 is disposed at the lower edge of the front wall 22 of the cabinet 21 for removing the punches as they are punched from the punchboard 28. Each punch, as it is punched from the punchboard, will effect the swinging of the contact plate 36 for closing at least one of the switches 40 which is connected into the electrical attraction circuit 47.

The electric attraction circuit 47 contained within the game device 20, described above, derives its energy from a transformer 48 which is adapted to be connected to a conventional 110 volt alternating current generally employed in homes, stores and other places where such a gaming device may be employed. The transformer 48 is adapted to be connected only to the attraction circuit 47, and a second transformer 49 will be connected to the inlet for the transformer 48 for illuminating the fixed lights 50 which may be supported on the front wall or face of the machine 21, as clearly noted in Figures 1 and 2 of the drawings. The lights 50 are adapted to be constantly in the circuit, whereas the attraction circuit 47 will only be energized upon playing of the device.

The attraction circuit 47 is provided with a master switch 51 supported in the cabinet 21 and the narrow end of the channel guide means defined by the guide channels 29 and 30. The master switch 51 is provided with a contact element 52 which faces in the direction from which the punchboard 28 is engaged, whereupon the engagement of the punchboard 28 into the channel guide means will effect the closing of the master switch 51, the master switch being normally biased to an open position.

Upon removal of a punch P from the punchboard 28, the contact plate 36 will engage at least one of the movable contact elements 42 of the switches 40 for closing and energizing the electric circuit 47. Immediately upon closing of the electric circuit 47, a solenoid or electromagnet 54 will be energized for actuating a chime 55 supported within the cabinet 21 and noted in Figure 3 of the drawings. Also, upon energizing the circuit 47, a second solenoid or electromagnet 56 will be energized for vibrating or otherwise actuating the contact plate 36 as suspended on the springs 37 and 38. The bumping solenoid 56 includes an armature 57 which engages the upper edge of the contact plate in the manner clearly noted in Figure 2 of the drawings,

the bumping of the contact plate 36 providing for the loosening of any punches which may be frictionally engaged between the contact plate 36 and the punchboard 28 spaced forwardly therefrom to provide for the free sliding movement of the selected punches downwardly through the channel 45 and outwardly through the lower funnel-shaped opening 46.

An attraction light 58 is connected in parallel with the chimes solenoid and the bumping solenoid, and will be illuminated at the time each punch is removed from the punchboard 28. The attraction light 58 may be viewed through an attraction window, or glass wall, 59 on the upper wall 24 of the cabinet 21, the attraction window 59 being provided with some sort of attractive decoration, as the four-leaf clover noted in Figure 1 of the drawings. An electrically operated counter member 60 is also connected in parallel with the solenoids and light 58, the counter 60 being viewable through a window 61 extending upwardly from the upper wall 24, as clearly noted in Figures 1, 2 and 3 of the drawings.

The electric motor 62 is also connected in parallel with the solenoids, the light 58 and the counter 60 to be energized as each punch is removed from the punchboard 28. A circular supporting disc 64 is positioned at one end of motor 62 for supporting a fixed contact element 65 to be engaged by a rotatable contact element 66 carried by the motor shaft 67. Upon closing of the attraction circuit 47, the motor shaft 67 will be caused to rotate and the movable contact element 66 will be caused to sweep about the surface of the supporting disc 64 and come in contact with the fixed contact element 65 at one point during each rotation thereof. There will be no definite timed relation between the selection of punches from the punchboard and the rotation of the motor shaft 67, so that the element of chance is introduced into the gaming device, the chance being when the fixed contact element 65 will be engaged by the rotatable contact element 66 and remain there until the circuit 47 should be again energized for further rotating the motor shaft 67. In other words, upon completion of the circuit 47, the motor 62 will be caused to operate and in the event that the rotatable contact element 66 should come to rest on the fixed contact element 65, a free play would be awarded. It is understood that as the shaft 67 rotates, the movable contact element will continually pass over the fixed contact element 65 and cause a flickering of the indicating light 68 which is connected to the fixed contact element. A buzzer or other alarm device 69 is connected in series with the free play light and the rotatable switch 70 defined by the contact elements 65 and 66, whereupon an alarm will be sounded when the rotatable contact element has come to rest on the fixed contact element 65. The buzzer or alarm 69 would be intermittent in its operation during the rotation of the shaft 67, but will be continual when the rotatable contact element 66 comes to rest on the fixed contact element 65.

As the operation of the attraction circuit 47 will be quite intermittent during the proper playing of a game, an alarm device 71 is connected in parallel with the solenoids, the lights, the counter and motor 62, the warning element 71 being of an audible nature to be set into continuous operation in the event that a punch P is caught in the channel 45 or in the event that the gaming device 28 is being operated in an

unauthorized manner, whereupon the punches would not slide freely for removal from the opening 46.

The punchboard 28 is particularly designed for the gaming device 20 described above and is formed with a plurality of apertures or bores 72 therethrough, in which the punches P are adapted to be engaged. The rear surface 74 of the punchboard 28 is of a more rigid nature than the material from which the punchboard 28 is generally formed, such as paper or the like, to provide for the free sliding movement of the punches therethrough in a manner to prevent the accidental snagging of the punches P in the rear ends of the bores 72, this structure being particularly designed for the free movement of the punches P as they are selected for removal from the punchboard to be dropped through the channel 45 and out through the opening 46 for the player. By placing the slick rear surface 74 on the punchboard, the punches are normally retained within the board spaced inwardly from the rear face, so that, upon removal of the punches, the small, snagged pieces of paper which normally retain the punches in the board and may at times extend rearwardly from the board when the punches are removed will be within the board to provide a slick surface on the punchboard to obstruct the free sliding movement of the punches P in the space 45 in no manner.

In order to provide a safety feature for the punchboard 28, it is intended that the direction of the bores 72 shall not be parallel and that no parallel relation will be provided between adjacent bores 72. In this manner, no comb-like device having a plurality of parallel prods may be used for removing a plurality of punches P at a single time. In other words, one of the bores 72 may be a bore perpendicular to the plane of one face of the punchboard 28, and the adjacent bore, as the bores 72a and 72b, will be disposed at an angle outwardly from the bores 72, or the bores adjacent the first bore 72 may be disposed at an upward and downward inclination. An indicating device 75 is shown on one end of each of the punches P for indicating the direction of inclination of the bores, but it is understood that no such indication will be used on the punchboard in use. In Figure 9 of the drawings, the indicating elements 75 are clearly noted, and those punches P without an indicating device 75 are adapted for straight punching or perpendicular to the front and rear surfaces of the punchboard 28. The bores 72a which are inclined at one direction from the perpendicular are indicated by the indicating elements 75a, and those punches in bores 72b are provided with indicating elements 75b. Those punches which are secured in bores which are inclined upwardly are provided with an indicator element 72c, and those in the downwardly inclined bore have an indicating element 72d, as clearly noted in Figure 9 of the drawings. The showing of the angled bores in the punchboard is merely exemplary, as it is understood that various angled rearrangements may be employed and in different sequences and arrangements.

In the use and operation of the gaming device 20 described above, the lead lines or wires 81 and 82 may be connected to a conventional type of electrical plug 84 for connection into an electrical socket of a conventional formation. Upon engagement of the plug 84 into the socket, the attraction lights 50 will be energized for indicating

that the gaming device 20 is set for operation. The person desiring to play the device 20 will pay the cost of selecting a punch to an attendant and then may employ the punching device 85 for removing a selected one of the punches P. A handle 33 is fixed on the punching device, and is preferably formed as a rabbit foot or other attractive and superstitious good luck piece. As the punch P is slidably moved from its respective bore in the punching device, the punch P will engage the contact plate 36 for moving the contact plate rearwardly within the cabinet 21 and closing at least one of the spring switches 41. Upon closing of the spring switches 41, the circuit 47 will be closed and the bumping solenoid 56 will be energized for bumping the contact plate 36 and effecting the free sliding movement of the selected punch P downwardly through the channel member 45 and outwardly through the opening 46. As the contacts 41 and 42 are in engagement, the chimes 55, actuated by the solenoid 54 will ring and the light 58 will be energized. Also, the motor 62 will be rotated, and in the event that the rotatable contact element 66 comes to rest in engagement with the fixed contact element 65, the free play light 68 will be connected in the circuit and the buzzer 69 will be connected for continued operation. As each punch P is removed from the punching device, the counter 60 will be energized for totaling the number of punches taken. The free play light is viewed through a window 63 in the front wall of the housing.

In the event that the warning bell or other audible element 71 is in continual operation, the attendant, through the gaming device 20, will be placed on notice that the gaming device is being used in an unauthorized manner, or that a punch P has become lodged between the punching device 28 and the contact plate 36 for maintaining the circuit 47 in a constantly closed condition.

The punching device 28 may be inserted into the machine through an opening 86 on one of the side walls of the cabinet, the opening 86 being adapted to be closed by a door or closure member 87 having a key lock 88 therein for securing the closure in a closed position. The opening 86 provides for the free sliding movement of the punching device 28 into and out of the channel guide members 29 and 30 on the rear side of the front wall 22 of the cabinet 21.

I do not mean to confine myself to the exact details of construction herein disclosed, but claim all variations falling within the purview of the appended claim.

I claim:

A game device comprising a housing having a front wall provided with an opening, a punch board removably mounted in said housing at the inner side of said front wall and in registry with said opening and having punches therein selectively movable out of said punch board and inwardly of said housing, a contact plate resiliently suspended in said housing adjacent and substantially parallel to the side of said punch board disposed inwardly of said housing and movable away from said punch board by punches punched from said punch board, a support plate fixedly mounted in said housing adjacent and substantially parallel to the side of said contact plate remote from said punch board, normally open resilient switches mounted in spaced apart relationship on said support plate at the side of the latter adjacent said contact plate and closed at random by said contact plate when the latter is moved away from said punch board, and an electric signal circuit including said switches in parallel and signal devices in series with said switches, said signal circuit including an electrically actuated vibrator mounted on said housing and engaging said contact plate to free punches caught in the space between said punch board and said contact plate and cause such punches to fall to the bottom of said space.

VERNON K. SMITH.
